To all whom it may concern:

Be it known that I, Sam'l H. To save labour in drawing, but one half of the ornaments upon the plates represented in Figs. 2 and 4, are delineated; the remaining portion being similar to, and symmetrical with those represented. The figures are not easily described in words, but are fully represented in the drawings. The borders indicated at a b & c d, are continued entirely around their respective panels.

What I claim as my invention, and desire to secure by letters Patent is the combination and arrangement of ornamental figures forming respectively the front side and rear plates of my stove, as herein represented and described.
